UNITED STATES PATENT OFFICE.

EMMIT G. LATTA, OF FRIENDSHIP, NEW YORK, ASSIGNOR OF ONE-HALF TO
HARVEY A. MOYER, OF SYRACUSE, NEW YORK.

TYPE-WRITING MACHINE.

No. 847,990.

Specification of Letters Patent.

Patented March 19, 1907.

Original application filed July 5, 1904, Serial No. 215,246. Divided and this application filed September 27, 1904. Serial No. 226,187.

To all whom it may concern:

Be it known that I, EMMIT G. LATTA, a citizen of the United States, residing at Friendship, in the county of Allegany and State of New York, have invented a new and useful Improvement in Type-Writing Machines, of which the following is a specification.

This invention relates to auxiliary carriage releasing and stop or feed mechanisms for type-writing machines of that kind in which the platen-carriage is moved horizontally by a driving-spring or power device and is controlled by a regular feed mechanism which operates upon the actuation of the type-bar keys and space-key to effect an intermittent or step-by-step movement of the carriage to produce the letter-spacing. The auxiliary carriage-stop mechanism hereinafter described is especially applicable to front-strike type-writing machines of the character disclosed in my application for United States Letters Patent filed July 5, 1904, Serial No. 215,246, in which the horizontally-movable carriage is mounted and moves on a vertical movable shift-frame; but the auxiliary stop mechanism is applicable to other forms of type-writing machines.

This application is a division of my application above identified.

The object of the invention is to provide an efficient desirable auxiliary carriage releasing and stop or feed mechanism for type-writing machines of simple and inexpensive construction, whereby the carriage can be readily released from its regular feed, allowed to move to and be arrested at different desired positions in its horizontal travel for the purpose of paragraphing and producing column and tabulated matter.

A further object of the invention is to improve the auxiliary carriage releasing and stop mechanisms for type-writing machines in the different particulars hereinafter pointed out, and set forth in the claims.

In the accompanying drawings, consisting of two sheets, Figure 1 is a longitudinal sectional elevation of a portion of a type-writing machine provided with an auxiliary carriage-stop mechanism embodying the invention. Fig. 2 is a fragmentary end elevation there-

of. Fig. 3 is a plan view, partly in horizontal section, thereof, the platen being omitted and parts being broken away to expose the under parts of the machine. Fig. 4 is a front elevation thereof without the platen. Fig. 5 is a transverse sectional elevation thereof in line 5-5, Fig. 1. Fig. 6 is a plan view of an auxiliary stop-bar of different construction detached. Fig. 7 is an elevation of one of the interchangeable auxiliary stop-strips, showing a different arrangement of the stop projections. Fig. 8 is a detail rear elevation of the carriage-escapement wheel and associated parts. Fig. 9 is a fragmentary section on an enlarged scale, showing the auxiliary stop-bar and adjacent parts.

Like letters of reference refer to like parts in the several figures.

A represents a portion of the stationary or main frame, which may be of any suitable construction, and B the carriage supporting and shifting frame described in my said application. This shift-frame in the construction illustrated is of rectangular form, consisting of front and rear cross-bars b' , connected by end and intermediate longitudinal bars b^2 , b^3 , respectively, and is pivoted at its rear portion to swing vertically on bearing-trunnions c , which are adjustably mounted on the rear portion of the sides of the main frame and enter sockets in the ends of the shift-frame. The latter is normally held up in the position shown in Fig. 1, as by a suitable spring D, secured to the back of the main frame, with its free front end bearing against the under side of the shift-frame, and is swung downwardly against the lifting action of said spring to shift the carriage by mechanism fully explained in my said application.

E represents the usual platen journaled to rotate on a carriage F, which preferably consists of end bars or pieces f , connected by a front cross-rod f' and a rear cross-bar or bearing-bar f^2 . The carriage is mounted to travel horizontally transversely of the machine, preferably on the front and rear sets of bearing-balls g^2 , g^4 , respectively, interposed between the rear bearing-bar f^2 of the carriage and a transverse bearing-bar G, fixed on the front part of the shift-frame. The

carriage extends forwardly from the shift-frame. The ball-bearing for the carriage is fully described in my said application. The carriage may be mounted to travel on the shift-frame in any other suitable manner, and it will be understood that the invention 5 to be hereinafter described is also applicable to machines in which the shift-frame is omitted and the carriage travels directly on the stationary main frame.

The regular feed or step-by-step movement of the carriage to produce ordinary letter-spacing is effected by an escapement mechanism, a portion only of which is shown 15 in Figs. 1, 3, 8, and 9.

N represents a toothed rack, which is secured to the under side of the bearing-bar f^2 of the carriage between the two rows of bearing-balls by the screw n , which fasten the 20 bearing-bar to the end pieces of the carriage or in any other suitable manner. O is an escapement-shaft, which is journaled at its ends in the front and rear cross-bars of the shift-frame and is arranged longitudinally of 25 said frame beneath the intermediate bar thereof, which is preferably concaved. The shaft is provided near its front end with a gear-pinion p , which projects through a slot in the bearing-bar G of the shift-frame and 30 meshes with the toothed rack N , and is provided at its rear end with an escapement-wheel p' , which is controlled by an escapement mechanism (not shown) to effect the step-by-step movement of the carriage. It 35 will be understood that, as usual, the carriage is connected to a driving-spring or other power device, which tends to move the carriage to the left, and that the escapement mechanism is operated through the medium 40 of the well-known universal bar whenever the type-bars or space-key are actuated.

p^2 is a dog pivoted on the rear of the main frame and engaging the teeth of the escapement-wheel to hold the latter from rotation. 45 The center of the escapement-wheel and the point at which the dog engages the teeth of the wheel are located in the pivotal axis of the shift-frame, so that the movement of the wheel on the holding-dog in shifting the carriage is so small that it is not an objection 50 and does not interfere with the easy proper action of the escapement in either position of the carriage. A similar result can be secured by pivoting the holding-dog on the shift-frame, with the joint connecting it with the universal bar also located in the pivotal axis of the shift-frame.

Q represents a carriage-release bar, which is arranged in rear of the platen adjacent to 60 and parallel with the front bar of the shift-frame. The release-bar is connected at opposite ends by upturned portions to arms q on the rear ends of shafts q' , journaled in the end bars of the carriage and provided at their

front ends with line-space levers q^2 . The arrangement and operation of the line-space levers and connecting carriage-release bar are fully described in my application for United States Letters Patent, Serial No. 208,011, filed May 14, 1904.

R , Fig. 3, is a rock-shaft journaled in suitable bearings on the shift-frame parallel with the escapement-shaft and provided at its front end with a crank-arm having a stud r situated over the carriage-release bar and at 75 its rear end with a crank-arm having a stud r' , which engages the holding-dog p^2 for the escapement-wheel. The rock-shaft R is held with its rear stud out of contact with the holding-dog p^2 and against a suitable 80 stop r^3 by a spring r^2 , coiled about the shaft and connected thereto and to the shift-frame. The stop r^3 shown consists of a slotted plate 85 adjustably secured on the rear of the shift-frame by a screw. By adjusting the stop the release-shaft can be arrested with its studs in position to work to the best advantage. When either line-space lever is rocked to turn the platen and feed the paper, the release-bar is lifted and engaging the front 90 stud of the release-shaft R oscillates the latter, so as to move the holding-dog p^2 out of engagement with the escapement-wheel and release the escapement to permit the free movement of the carriage.

The auxiliary feed or stop mechanism for setting the carriage to different predetermined positions for paragraphing and producing column-work is constructed as follows:

S represents a feed-bar arranged adjacent to and parallel with the carriage-release bar in rear of the platen and carried by forwardly-projecting arms s at its ends, which are removably hung to oscillate vertically on the front cross-rod j' of the carriage by 100 hooks s' or otherwise. Both arms preferably project forwardly from the carriage and are connected to a finger-bar s^2 , which is parallel with the carriage and located just above the rear portion of the keyboard. The arms 105 s of the feed-bar are preferably curved, as shown in Fig. 1, and bowed outwardly, as shown in Fig. 3, to avoid interference with the type-bars when the carriage is at either end of its run. The feed-bar is normally held down in the position shown by full lines in Fig. 1 beneath and out of engagement with the front stud of the release-shaft R by a suitable spring s^3 , Fig. 2, secured to the carriage and bearing against one arm of the 110 feed-bar. The latter is provided with a number of upwardly-extending stop projections t to coöperate with a fixed stop T on the shift-frame to arrest the carriage in 115 different positions, determined by the location of the stop projections t and fixed stop T . The stop projections t are preferably formed on a hardened-steel stop-strip t' ,

which is removably seated in a groove in the feed-bar, in which it is held from transverse movement by the engagement of pins t^2 , Figs. 4 and 9, in a longitudinal groove t^3 in the 5 stop-strip. The stop-strip is slipped endwise into the groove in the feed-bar and is held from endwise movement therein when the feed-bar is in normal position by the engagement of its ends with the end bars of 10 the carriage.

The operation of the auxiliary feed mechanism is as follows: By partially depressing the finger-bars s^2 the stops t on the feed-bar are raised into line with the fixed stop T , and 15 by further depressing the finger-bar the rear edge of the feed-bar engages the front stud of the release-shaft R and rocks the same to release the carriage, as before explained. The carriage is then free to move to the left until 20 arrested by the engagement of one of the stop projections t with the fixed stop T . Upon releasing the finger-bar the feed-bar S permits the release-shaft to rock far enough to allow the holding-dog p^2 to swing into position 25 to intercept the escapement-wheel before the stop on the feed-bar is free from the fixed stop T , and upon the complete return of the feed-bar the carriage is again controlled by the regular step-by-step escapement. The 30 stop projections are situated at ten letter-space intervals on the stop-strip or at other desired intervals such as to arrest the carriage at the desired points, and the first stop projection is preferably so located as to stop 35 the carriage in correct position for starting a paragraph. Interchangeable stop-strips provided with differently-spaced stop projections are provided, so that by placing the proper strip on the feed-bar the carriage can 40 be stopped at various desired points, thus greatly facilitating the production of different kinds of column or tabulated work. A stop-strip t^4 , with a different arrangement of stop 45 projections, is shown in Fig. 7. The fixed stop T is also preferably adjustable on the shift-frame, for which purpose in the construction shown it consists of a block having teeth on its rear face, which are held in engagement with co-operating teeth u on the 50 front bar of the shift-frame by a holding-screw or other releasable securing device u' . (See Fig. 3.) By adjusting the fixed stop T along the shift-frame the paragraphing-stop may be caused to act at any desired point 55 near the left end of the line, and a similar adjustment may be used to vary the relative points in the line at which the carriage is arrested by the column-stops. Thus in column-work, while with the same stop-strip the 60 columns would always be the same distance apart, their relative location on the sheet could be changed at will. The finger-bar is in a most favorable position to be reached, and it

can be operated by downward pressure on any part of its length; but as it moves laterally with the carriage the operating pressure will ordinarily be applied to that part which happens to be opposite the central part of the keyboard. An important advantage of this construction is that the operator's finger follows the movement of the finger-bar with the carriage and acts as a brake to prevent to a great extent the shocks, strains, and wear which would be caused by the abrupt stopping of the carriage after moving a long distance.

Fig. 6 shows a modified form of feed-bar S' for the auxiliary feed mechanism in which the finger-bar is omitted, and one of its arms terminates in an operating-lever S^2 . This 80 bar is interchangeable with the feed-bar S , before described. It is lighter and less expensive, but lacks the advantages of the finger-bar. By first removing the platen from the carriage the feed-bar in either form can 85 be readily unhooked and lifted off of the carriage, leaving in place as the only parts of the auxiliary stop mechanism the spring s^3 and the fixed stop T on the shift-frame. The auxiliary feed device requires but little force 90 to operate it and can be operated without shifting the carriage, if desired; but by the application of more force to the feed-bar it serves the double function of shifting the carriage and at the same time moving the carriage an irregular distance to a desired position. This is an advantage in paragraphing, 95 as a capital letter or upper-case character is usually required to start the paragraph, and this double function of the feed-bar saves one 100 motion. When the carriage is locked in shifted position for the use of upper-case characters only, the operation of the auxiliary feed device has no effect on the carriage-shift.

In machines in which the carriage is mounted directly on the stationary main frame the parts which are above described as mounted on the shift-frame will of course be mounted on suitable parts of the stationary 110 main frame. This will be manifest if the shift-frame be considered as a fixed part of the main frame instead of as a separate pivoted frame.

I claim as my invention—

1. In a type-writing machine, the combination with a platen-carriage, a supporting-frame therefor, and a step-by-step feed, of an auxiliary feed comprising a relatively fixed stop, and a combined releasing and stop bar 115 mounted on the carriage in rear of the platen and between the platen and the carriage-supporting frame and movable to release the step-by-step feed and place a stop thereon in position to engage said fixed stop to arrest the carriage, the movable bar having a rig- 120

idly-connected forwardly-projecting lever by which it is actuated, substantially as set forth.

2. In a front-strike type-writing machine, the combination with a carriage, and a step-by-step feed, of an auxiliary feed mechanism comprising a relatively fixed stop, and a device supported by and movable with the carriage and having a horizontal bar which is movable vertically to place a stop thereon in position to engage said relatively fixed stop, and an operating finger-bar connected to said stop-bar and located in front of the carriage and parallel with the platen in position to allow the type-bars to swing between it and the platen, said finger-bar being of such length that some part thereof will be at the central portion of the machine in all positions of the carriage, substantially as set forth.

3. In a type-writing machine, the combination with a carriage, and a regular step-by-step feed, of an auxiliary feed device comprising a fixed stop on the carriage-supporting frame, a bar pivoted on the carriage, a detachable stop-strip having a series of stops supported by said bar, and a lever rigidly connected to said bar for swinging the bar to place the stops on the bar in line with the fixed stop on the frame, substantially as set forth.

4. In a type-writing machine, the combination with a carriage, and a regular step-by-step feed, of an auxiliary feed comprising a fixed stop and a rigid rectangular frame pivotally connected to the carriage and having a rear bar supporting a series of stops, and a front bar located forwardly of the carriage to serve as a finger-lever to actuate the frame, substantially as set forth.

5. In a type-writing machine, the combination with a carriage, and a regular step-by-step feed, of an auxiliary feed comprising a fixed stop and a rigid rectangular frame having ends centrally pivoted to the ends of the carriage, a rear bar supporting a series of stops, and a front bar located in front of the carriage and forming a finger-lever to actuate the frame, substantially as set forth.

50 6. In a type-writing machine, the combination with a carriage, and a regular step-by-step feed, of an auxiliary feed device comprising a fixed stop, a movable bar on the carriage having a longitudinal groove, a strip provided with stops detachably retained in said groove, and means to prevent lateral displacement of the stop-strip, substantially as set forth.

60 7. In a type-writing machine, the combination with a regular step-by-step feed, of an auxiliary feed device comprising a fixed stop, a swinging bar pivoted to the carriage, and an endwise detachable stop-strip supported on the swinging bar and arranged between

parts at the ends of the carriage so that the 65 stop-strip is held against endwise movement on the bar by the carriage when in operative position, substantially as set forth.

8. In a type-writing machine, the combination with a carriage, and a step-by-step feed, of an auxiliary feed mechanism including a device removably hung on the carriage beneath the platen to oscillate vertically and travel with the carriage, and adapted to be detached from and placed on the carriage 75 when the platen is detached without the actuation of securing devices, substantially as set forth.

9. In a type-writing machine, the combination with a carriage, of feed mechanism 80 for the carriage including a feed-bar having side arms extending beneath the platen and provided with hooks removably seated on parts of the carriage, said hooks forming pivotal supports for the feed-bar and enabling it 85 to be readily attached to and detached from the carriage, substantially as set forth.

10. In a type-writing machine, the combination with a movable carriage, and a step-by-step feed, of a carriage-releasing bar, and 90 an auxiliary carriage releasing and stop bar, said bars being arranged adjacent to each other and operating independently to release the step-by-step carriage-feed, substantially as set forth.

95 11. In a type-writing machine, the combination with a movable carriage, and a relatively stationary step-by-step carriage-feed, of a carriage-releasing bar, and an auxiliary carriage releasing and stop bar, said bars 100 being mounted parallel with each other on the carriage and operating independently to release the step-by-step carriage-feed, substantially as set forth.

105 12. In a type-writing machine, the combination with a movable carriage, a relatively stationary step-by-step carriage-feed, and a carriage-stop, of a carriage-releasing bar, and an auxiliary carriage releasing and stop bar, said bars 110 being arranged parallel with each other and movable with the carriage and being also movable independently to actuate the same part of the carriage-feed to release the carriage, substantially as set forth.

115 13. In a type-writing machine, the combination with a platen-carriage, a supporting-frame for the same, and a regular step-by-step feed, of auxiliary feed mechanism comprising a stop on said supporting-frame, a carriage releasing and stop bar located between the platen and said supporting-frame 120 parallel with the platen, and arms rigidly connected to the ends of said stop-bar and pivoted to the carriage, one of said arms extending forwardly beneath the platen-shaft 125 for operating said stop-bar, substantially as set forth.

14. In a type-writing machine, the combi-

nation with a platen-carriage, a supporting-frame for the same, and a regular step-by-step feed, of auxiliary feed mechanism comprising a stop on said supporting-frame, a carriage releasing and stop bar located between the platen and said supporting-frame parallel with the platen, and arms rigidly connected to the ends of said stop-bar and pivoted to the carriage, said arms extending

forwardly beneath the platen-shaft and being connected by a horizontal operating finger-bar, substantially as set forth.

Witness my hand this 21st day of September, 1904.
